UNITED STATES PATENT OFFICE.

JAMES A. GREENLEE, OF CHICAGO, ILLINOIS, AND HERMAN WEGWART, OF BURLINGTON, WISCONSIN, ASSIGNEES TO THE G & W PACKAGE COMPANY, OF CHICAGO, ILLINOIS, A CORPORATION OF ILLINOIS.

BASKET.

1,294,093.

Specification of Letters Patent. Patented Feb. 11, 1919.

Application filed May 20, 1918. Serial No. 235,744.

To all whom it may concern:

Be it known that we, JAMES A. GREENLEE and HERMAN WEGWART, citizens of the United States, and residents of the city of 5 Chicago, county of Cook, and State of Illinois, and the city of Burlington, Racine county, and State of Wisconsin, respectively, have invented certain new and useful Improvements in Baskets, of which the following is a specification.

Our present invention relates to baskets or similar receptacles, and particularly baskets fabricated of splints or veneer and woven or interwoven on what is commonly known as 15 the "diamond splint" principle or "basket weave." The primary object of our present invention is the provision of a basket that is reinforced so that it shall be capable of withstanding all the usual strains or 20 tensions put upon it when employed in shipping commodities, and at the same time will retain the flexibility which lends to this variety of structure its peculiar strength, and also it is desirable to secure the reinforcement with the addition of as little 25 extra weight as possible.

Baskets woven of crossed or interwoven splints and provided with the usual upper rim are usually well adapted for conveying 30 articles or commodities when the container or receptacle is carried upon the arm of the user. When, however, these woven baskets are stacked the one upon the other, the weight of the upper baskets upon the lower 35 baskets will squeeze or push out or bulge the portions of the splints forming the sides and ends of the baskets to an extent where the splints will be damaged and will not recover their original form after the weight 40 has been removed. The stacking of the baskets will also frequently cause the upper ends of the splints to break away from the rim which will result in a loss of the commodities contained within the basket, as 45 well as leave the basket unhandy and cumbersome for future handling. Also in the shipment of commodities, such as sides or shoulders of bacon and other long and narrow articles, when the baskets are packed 50 and being handled the persons doing so frequently carry them end down, thus permitting the commodities to settle toward one end and the entire weight of the contents is then disposed against and borne by the

splints at the lower end of the basket, which, 55 of course, strains and weakens and frequently breaks the splints away from their fastening.

It is one of the objects of our invention to provide a reinforcing for a splint or 60 woven basket that will strengthen the basket at its ends or sides, or both, without interfering with the original flexibility of the structure, and will prevent the strain incident to the stacking of a number of baskets 65 from bulging or weakening the splints beyond their power of recovery. It is also an object of our invention to provide means in a splint basket whereby, when it is carried one end down, the splints at the lower 70 end will be protected and reinforced so as to prevent their tearing away from their securing means. It is a further object of our invention to provide a reinforcing device that is dependable and capable of supporting a considerable weight, yet fabricated from relatively thin and inexpensive material. Other objects are the provision 75 of a shipping basket of the splint type that shall be economical to manufacture and dependable in carrying out the functions for 80 which it is designed.

We prefer to accomplish the divers objects of our invention in substantially the manner and by the means hereinafter fully 85 described and as more particularly pointed out in the claims, reference now being had to the accompanying drawings that form a part of this specification, wherein,—

Figure 1 is a central longitudinal section 90 of a basket constructed in accordance with the principles of our invention.

Fig. 2 is a transverse vertical section thereof taken on line 2—2 of Fig. 1.

Fig. 3 is a view similar to Fig. 1, showing 95 the basket compressed.

Fig. 4 is an outside end view of a modified disposition of the reinforcing member.

Referring to the drawings, and more particularly to Figs. 1, 2 and 3, it will be observed the basket preferably consists of a body portion formed of interwoven splints, the splints being crossed and woven together in what is commonly called the "basket weave", or what is known by the trade name 100 of "diamond braiding." This braiding may be done with single crossed splints, in the manner of ordinary basket structures, or

the splints may be of a double weaving to provide two bodies interwoven at their ends or corners, as disclosed in our prior Letters Patent of the United States, No. 1,153,096, 5 issued to us September 21, 1915, for improvements in a basket. For the purpose of clearness, however, we have shown the braiding done with single crossed splints 5 and 6.

A suitable frame is provided, consisting of 10 end pieces 7 and longitudinal side pieces 8, that surround and have the upper ends of the splints secured thereto by tacking, stapping, or in any other suitable manner. The inner portions of the upper edges of the 15 splints are bound by a suitable thin strip of material 9, that is secured in position by tacks, nails or staples, that are driven through the same and through said splints into the outside frame.

20 In order to reinforce and to render more stable the body of the basket, we have provided suitable aprons 10—10 that are secured adjacent their upper ends to the upper portions of the basket and extend down 25 alongside the walls thereof. Divers dispositions of these aprons may be made; for example, as shown in Figs. 1, 2 and 3, they are positioned inside the basket at the ends thereof and are secured between the inner 30 binding strip 9, and the splints are of a length or height to have their lower edges disposed adjacent to the bottom of the basket, where the corner edges begin to curve under so as to limit the amount of compressibility to which the woven splints will be subjected.

It may be found desirable to position these 40 aprons upon the inside of the longitudinal sides of the basket, as shown in dotted lines in Fig. 1 of the drawing, in which event they will be secured to the side of the basket between the retaining strips 9 and the upper ends of the splints. A still further disposition of these aprons may be made by 45 placing them upon the exterior of the ends of the baskets, as shown in Fig. 4, in which event they will preferably be inserted between the outer surfaces of the splints and the usual longitudinally disposed runners 11 50 that extend along the bottom and up the ends of the basket.

From the above it will be seen that when 55 the basket is positioned upon its bottom and additional weight placed upon the top, such as would result from stacking a number of loaded baskets, the bottom baskets will flatten until the lower edge of the apron comes into contact with the portion of the basket disposed upon the support and said

aprons will take up the remaining stress to 60 which the basket will be subjected and thereby limit the displacement of the splints as shown in Fig. 3 of the drawings. These aprons are usually made of veneer or strips of wood of divers thicknesses and, owing to 65 their substantially vertical disposition, they are capable of supporting a greater amount of pressure or weight than the thinner splints would be.

We desire it understood that we do not 70 limit ourselves to the precise location of these aprons with respect to the walls of the basket structure, nor to the type of braiding or weaving the splints, for it is quite obvious that divers changes or alterations may be 75 made without materially departing from the spirit of our invention. We therefore desire it understood that such changes or modifications may be made without materially departing from the principles of our 80 invention as expressed in the appended claims.

What we claim is:—

1. A basket or like receptacle comprising a woven body portion consisting of a bottom, 85 side walls and end walls, and an apron secured only to the upper portion of one of said walls and terminating a slight distance above said bottom said apron being wide enough to take the thrust of the contents of 90 said basket.

2. A basket or like receptacle comprising a flexible woven body portion consisting of a bottom, side walls and end walls, and oppositely disposed aprons positioned inside 95 said basket and secured only to the upper portions of said walls, the lower edges of said aprons terminating slight distances above said bottom said aprons being wide enough to take the thrust of the contents of 100 the basket and thereby limit the flexibility of said walls.

3. A basket or like receptacle comprising a body of woven flexible splints, a frame to which the upper edges of said body are secured, and aprons only the upper portions whereof are secured to said frame and the lower portions depend inside and adjacent the side walls of said body said aprons being wide enough to take the outward thrust 105 of the contents of said basket.

Signed at Chicago, county of Cook and State of Illinois, this 16th day of May 1918.

JAMES A. GREENLEE.
HERMAN WEGWART.
